UNITED STATES PATENT OFFICE.

LAWRENCE ALLENBRAND, OF BASEHOR, KANSAS.

CAR-BRAKE.

No. 866,904.

Specification of Letters Patent.

Patented Sept. 24, 1907.

Application filed April 11, 1907. Serial No. 367,519.

To all whom it may concern:

Be it known that I, LAWRENCE ALLENBRAND, a citizen of the United States, residing at Basehor, in the county of Leavenworth, State of Kansas, have invented 5 certain new and useful Improvements in Car-Brakes; and I do hereby declare the following to be a full, clear, and exact description of the invention, such as will enable others skilled in the art to which it appertains to make and use the same.

10 This invention relates to new and useful improvements in brakes for street cars, and it has particular reference to a brake involving a manually operated lever, transmission connections and brake beams operated from said lever and carrying brake-shoes.

15 In connection with a brake of the above type, the invention aims as a primary object to provide a novel construction, combination, and arrangement of parts, the details of which will appear in the course of the following description in which reference is had to the 20 accompanying drawings forming a part of this specification, like characters of reference designating similar parts throughout the several views, wherein:

Figure 1 is a central longitudinal section of a street-car brake constructed in accordance with the present 25 invention; parts being shown in elevation. Fig. 2 is a top plan view thereof, the floor of the car being indicated by dotted lines. Fig. 3 is a vertical transverse section on the line 3—3 of Fig. 2, showing the brake beams and their associated parts. Fig. 4 is a 30 detailed perspective view of a bracket, in which a connecting lever is pivoted.

Referring specifically to the accompanying drawings, the numeral 1 designates the floor of the car, from which is suspended, rearwardly of the motorman's platform, 35 a casing 2, the latter being supported in spaced relation to said floor and comprising a top 3, and depending sides 4, the ends and bottom of said casing being open in order to permit of the movement of the brake beams therethrough. A tubular member 5 is supported vertically upon the front end of the platform 1 and has open ends, the member 5 being in registry with an opening 6 provided in said floor. Projecting forwardly from the casing 2 is a bracket, which is illustrated more particularly in Fig. 4. This bracket designated by 40 the numeral 7 comprises a U-shaped open ended body portion formed at its rear end with a depending apertured projection 8, by means of which it is secured to the front side wall of the casing 2.

A transmission lever 9 is pivoted at a point adjacent 50 its front end, as at 10, between the vertical sides of the bracket 2. Said lever at its rear end has pivotal connection, as at 11, with the vertically extended arm 12 of a brake beam 13, said brake beam being formed with depending spaced apertured ears 14 between which is

pivotedly received the upper end 15 of a brake beam 16, the brake beam 16 being twisted, midway its length to dispose said upper end in a vertical plane. The brake beams 13 and 16 are disposed in divergent relation, and at their outer ends carry brake-shoes 17 which are designed for frictional engagement with the track wheels 18. In their divergent relation the brake beams 13 and 16 are supported between respective pairs of spaced transverse friction rollers 19, the latter being freely mounted upon pins 20 having their ends mounted in the side walls 4, and being disposed transversely therebetween. The lever 9, at its front end, is enlarged and formed with an opening 21. Above said opening is a bearing plate 22, which registers therewith, and a similar constructed bearing plate 23 is fixed on said lever below said opening. A vertically 70 movable rod 24 is disposed in the member 5 and is formed with a reduced lower end 26 which projects through the bearing plates 22 and 23, and the opening 21 and which carries on its threaded end an adjusting nut 27, designed to so proportion the parts as to multiply or decrease movement of the lever 9, said lever being operated from the rod 24. Surrounding said rod is an expansive coil spring 28 having an end fixed thereto and bearing with its lower end against the plate 22. The rod 24 at its upper end, has pivotal connection, as at 29, with the front end of an operating lever 30, the latter being pivoted as at 31 between rearwardly extending spaced parallel ears 32, cast integral with the member 5. The ears 32 are constructed on their vertical rounded faces with rack teeth 33, and the lever 30 carries a sliding spring-pressed pawl 34, having an enlarged working end which is designed for engagement with said rack teeth.

The manner of operation will be readily apparent from the foregoing description. Downward movement of the lever 30 raises the rod 24, and the latter, by virtue of the connections described, raises the front end of the lever 9, the rear end thereof being lowered to force the brake beams 13 and 16 outwardly, whereby their brake-shoes 17 will frictionally engage the track, 95 and stop the movement of the car, it being of course understood that the power has been previously cut off. In like manner, upward movement of the lever 30 reverses the above operation and releases the brake-shoes from the track wheel. The spring 28 serves as a 100 cushioning element as well as a yieldable fastening means for the rod 24, and prevents the parts from becoming affected by sudden shocks and vibrations.

From the foregoing description, it will be seen that simple and efficient means are provided for accomplishing the objects of the invention, but, while the elements herein shown and described, are well adapted to serve the functions set forth, it is obvious, that

various minor changes may be made in the proportions, shape, and arrangement of the several parts, without departing from the spirit and scope of the invention as defined in the appended claims.

5 What is claimed, is:

A car brake of the type set forth comprising an operating lever mounted for pivotal movement on the platform of a car, a casing suspended from said platform, brake beams pivoted to one another at their upper ends and supported in said casing in divergent relation, and for downward and outward movement through the ends thereof, brake-

shoes carried by said beams, one of said beams having an extension, a stationary bracket, a lever pivoted between its ends in said bracket, and at its rear end to said extension, and an operative connection between said lever and said operating lever.

In testimony whereof, I affix my signature, in presence of two witnesses.

LAWRENCE ALLENBRAND.
